Patented May 7, 1918.

Inventor
Harry C. Adam.

UNITED STATES PATENT OFFICE.

HARRY C. ADAM, OF ST. LOUIS, MISSOURI.

DESIGN FOR A SEMI-INDIRECT LIGHTING-FIXTURE REFLECTOR.

52,001.

Specification for Design.

Patented May 7, 1918.

Application filed September 21, 1917. Serial No. 192,597. Term of patent 14 years.

To all whom it may concern:

Be it known that I, HARRY C. ADAM, a citizen of the United States, residing at St. Louis, Missouri, have invented a certain new, original, and ornamental Design for a Semi-Indirect Lighting-Fixture Reflector, of which the following is a specification, reference being had to the accompanying drawing, forming part thereof.

The figure of the drawing is a perspective view of my new design for a semi-indirect lighting fixture reflector.

I claim:

The ornamental design for a semi-indirect lighting-fixture reflector, as shown.

HARRY C. ADAM.
